UNITED STATES PATENT OFFICE.

WILLIAM C. BRAY, OF NEWTON, MASSACHUSETTS.

DESIGN FOR A RIVET.

SPECIFICATION forming part of Design No. 27,569, dated August 24, 1897.

Application filed December 2, 1896. Serial No. 614,244. Term of patent 14 years.

To all whom it may concern:

Be it known that I, WILLIAM C. BRAY, of Newton, in the county of Middlesex and State of Massachusetts, have invented and produced a new and original Design for Rivets, of which the following, taken in connection with the accompanying drawings, is a specification.

Figure 1 of the drawings is a plan of a rivet, showing my design; Fig. 2 an elevation of the same, and Fig. 3 is a central vertical section of the same on line $x-x$ on Fig. 1.

The leading feature of my design consists in a rivet provided with a tubular cylindrical shank and a head having a smooth circular outer edge, a convex upper surface upon which is formed in relief a representation of an eight-pointed star comprising a central hub having a convex outer surface and two sets of radiating points of different lengths, the outer surfaces of which are rounded or convexly curved transversely.

In the drawings, II is the rivet-head, the main body of the outer surface of which is

convex and the outer edge of which is a smooth or unbroken circle, and the inner surface is an annular flat plane surrounding the shank or attaching member S.

The convex outer surface of the head II has formed thereon a representation of a star raised above the convex outer surface of said head and comprising the central hub h , having a rounded outer surface and two sets of radiating points p and p' of different lengths and having their outer surfaces rounded or convexly curved transversely, said points p' alternating with the points p , as shown.

What I claim is—

The design for a rivet substantially as herein shown and described. 40

In testimony whereof I have signed my name to this specification, in the presence of two subscribing witnesses, on this 28th day of November, A. D. 1896.

WILLIAM C. BRAY.
